UNITED STATES PATENT OFFICE.

WILLIAM S. PORTER, OF BINGHAMTON, NEW YORK, ASSIGNOR TO S. CHENEY & SON, OF MANLIUS, NEW YORK, A CORPORATION OF NEW YORK.

GRINDER.

1,119,723.

Specification of Letters Patent.

Patented Dec. 1, 1914.

Application filed September 11, 1914. Serial No. 861,211.

To all whom it may concern:

Be it known that I, WILLIAM S. PORTER, of Binghamton, in the county of Broome, in the State of New York, have invented new and useful Improvements in Grinders, of which the following, taken in connection with the accompanying drawings, is a full, clear, and exact description.

This invention relates to certain improvements in grinders, and more particularly to an attachment adapted to be used in connection with an ordinary grinder in sharpening mower knives and similar articles.

The primary object of the invention is to provide a device which may be rigidly and quickly attached to a grinder when it is desired to use the same in sharpening mower knives and such articles, and which may be readily removed so that the grinder may be used for ordinary shop grinding or other purposes.

Other objects and uses will appear from the following description, taken in connection with the accompanying drawings, in which—

Figure 1 is a side elevation of a grinder having the attachment secured thereto. Fig. 2 is a top plan view of the same. Fig. 3 is a cross section on line 3—3, Fig. 1. Fig. 4 is a cross section on line 4—4, Fig. 2. Fig. 5 is a cross section on line 5—5, Fig. 2.

The device illustrated in the drawings comprises a frame or body portion in the form of a case —1— having a pair of laterally projecting horizontally disposed arms —2— and —3—, respectively, and below the arms —2— and —3— a third laterally projecting horizontally disposed arm —4—, all arranged and positioned so that the arms —2— and —3— are adapted to rest upon the surface of a bench, table or other suitable supporting means, and the arm —4— to project beneath the bench or table, the latter arm provided with an internally threaded opening for the reception of an adjustable externally threaded clamping bolt —5— adapted to clamp the frame to the supporting means.

The case —1— incloses a relatively large gear —6— mounted upon a shaft —7— journaled in bearings —8— and —9— in opposite sides of the case, and this shaft —7— may be rotated to rotate the gear —6— by means of a suitable operating handle —10—

mounted on a projecting end of said shaft. 55 The gear —6— is in mesh with a relatively small gear —11—, preferably formed integral with a shaft —12— likewise journaled in bearings formed in opposite sides of the case —1— and having a projecting 60 end upon which is mounted a suitable grinding or abrasive element —13—.

Projecting from the case —1— is a suitable slotted arm —14— upon which is adjustably mounted a tool shelf —15—, said 65 shelf adapted to be held in any desired position, either vertically or horizontally, by means of a bolt —16— seated in the respective slots in the arm and the base of the shelf. 70

The device so far described is adapted for general use in grinding tools of any kind.

The removable attachment for use in 75 grinding mower knives and similar articles comprises a platform —17— having a pair of vertically projecting spaced arms —18— and —19—, respectively, adapted to contact with one face of the case —1— and disposed upon opposite sides of the horizontally disposed arms —2— and —3— and contacting therewith to prevent horizontal movement of the platform when secured to the case by means of a pair of spaced clamping members —20— and —21— spaced apart a sufficient distance to receive between them the case —1— and pivotally mounted upon the platform —17— by means of bolts —22— and —23—, respectively, to swing horizontally about the case —1—, each arm provided with a threaded opening in its free end adapted to receive threaded clamping bolts —24— and —25—, respectively, for removably clamping the platform —17— to the case —1—. 85 90 95

The under side of the platform —17— is provided with a pair of legs —36— and —37—, respectively, spaced apart a distance equal to the distance between the arms —2— and —3— and so positioned laterally 100 of the platform as to rest upon the outer portions of the arms —2— and —3—, respectively, and support the platform, when clamped to the case —1— by means of the clamping members —20— and —21—, 105 against vertical and downward movement.

The opposite end portions of the platform —17— are somewhat raised or offset

above the plane of the platform and are provided with openings —26— and —27— for receiving and pivotally supporting a knife-rest —28— having a curved end —29— for receiving the knife-holders or cutter-bar. The central portion of the platform —17— at its outer edge is provided with a longitudinal slot, and a suitable vertically disposed bracket —30— is adjustably connected to the platform by means of a bolt —31— passing through the slot in the platform and through an opening in a horizontally disposed portion of the bracket. A second knife-rest —32— is pivotally mounted upon the upper free end of the bracket —30— to swing toward and away from the abrasive wheel —13—, and the bracket —30— and knife-rest —32— are provided with co-acting stops or lugs —33—, and —34— and —35—, respectively, for preventing relative movement of the parts beyond a predetermined point.

When it is desired to use the grinder for grinding mowing machine knives and similar articles, the platform —17— with its knife-supporting elements is readily and quickly attached to the case —1— of the grinder by merely placing it against the grinder so that the arms —18— and —19— contact with the arms —2— and —3—, and then swinging the clamping members —20— and —21— about the case —1— and adjusting the clamping screws —24— and —25—, and when it is desired to use the grinder for other purposes, the attachment may be readily removed by merely loosening the clamping screws and withdrawing the clamping members from about the case —1—.

Although I have illustrated and described one particular form of attachment and means for attaching the same, it will be readily apparent that changes may be made in the details of construction, arrangement and operation, without departing from the spirit of this invention as set forth in the appended claims.

What I claim is:

1. In a device of the class described, a frame having a laterally projecting arm

upon one side thereof, a platform resting 50 upon said arm, and means for clamping the platform to the frame.

2. In a device of the class described, a frame having a laterally projecting arm upon one side thereof, a platform, a leg depending from the platform and resting upon the laterally projecting arm, and means for clamping the platform to the frame.

3. In a device of the class described, a grinder frame having laterally projecting 60 arms, a platform having arms contacting with said laterally projecting arms to prevent horizontal movement of said platform, and means for clamping the platform to the frame.

4. In a device of the class described, a grinder frame having laterally projecting arms, a platform having vertically disposed arms contacting with the laterally projecting arms to prevent horizontal movement 70 of said platform, legs upon said platform and resting upon the laterally projecting arms to support the platform, and means for clamping the platform to the frame.

5. In a device of the class described, a 75 grinder frame having a laterally projecting arm forming a portion of the means for attaching the frame to a support, a platform resting upon the laterally disposed arm, and means for clamping the platform to the 80 frame.

6. An attachment for grinders comprising a platform, a knife-support mounted thereon, and clamping members pivotally mounted on the platform and adapted to 85 removably clamp the platform to a grinder frame.

7. An attachment for grinders comprising a platform, a knife-support mounted 90 thereon, and clamping members mounted on the platform and adapted to removably clamp the platform to a grinder frame.

In witness whereof I have hereunto set my hand this 2nd day of September 1914.

WM. S. PORTER.
